United States Patent Office.

ENOS T. HIGHAM, OF PHILADELPHIA, PENNSYLVANIA, ASSIGNOR TO HIMSELF AND DANIEL HIGHAM, OF SAME PLACE.

Letters Patent No. 105,573, dated July 19, 1870; antedated July 9, 1870.

IMPROVED SHADE-CORD RETAINER.

The Schedule referred to in these Letters Patent and making part of the same

I, ENOS T. HIGHAM, of Philadelphia, county of Philadelphia, State of Pennsylvania, have invented an Improved Shade-cord Retainer of which the following is a specification.

Nature and Object of the Invention.

My invention consists of the combination, described hereafter, of a plate having a yoke and thumb-screw, with a wedge-shaped bar; having a stud or its equivalent for receiving the shade-cord, the whole forming a cheap, simple, and effective self-tightening cord-retainer.

Description of the Accompanying Drawing.

Figure 1 is a perspective view of my improved shade-cord retainer, and

Figure 2, a vertical section of the same.

General Description.

A is a plate secured to the window-frame, and having a yoke or staple-like projection, through the front of which passes a thumb-screw.

B is a metal bar of the wedge shape, represented and fitted snugly, but so as to slide freely in the yoke of plate A, the upper thin end of the bar being provided with a suitable stud, d, round which passes the shade-cord E, and the lower and thicker end of the bar having a lug, e, which, together with the said stud

d, prevents the detachment of the bar from the plate A.

Difficulty is experienced with many of the cord-retainers in common use, to prevent the adjustable stud, round which the cord passes, from slipping, the necessary tension imparted to the cord frequently exerting such force on the stud and its appendages, that a sudden releasing of the stud, and consequent running down of the shade, takes place. It will be seen that, in my device, the greater the tension imparted to the cord is, the tighter will be the hold of the bar, owing to its wedge-like shape on the permanent plate A, and the tighter will be the screw, owing to the action of the wedge. Even if the screw should accidentally become loose, it cannot permit the wedge-shaped bar to rise to any great height, before it, as well as the screw, again becomes tighter.

Claim.

The combination of a plate, A, yoke, a, and thumb-screw, b, or its equivalent, with the wedge-shaped bar B, and the stud d, or its equivalents, for receiving the cord E.

In testimony whereof I have signed my name to this specification in presence of two subscribing witnesses.
